UNITED STATES PATENT OFFICE.

HENRY M. SKINNER, OF ROCKFORD, ASSIGNOR OF ONE-HALF TO IRA M. ALVORD, OF CHICAGO, ILLINOIS.

PLOW.

SPECIFICATION forming part of Letters Patent No. 324,789, dated August 18, 1885.

Application filed November 19, 1884. (No model.)

To all whom it may concern:

Be it known that I, HENRY M. SKINNER, a citizen of the United States, residing at Rockford, in the county of Winnebago and State 5 of Illinois, have invented a new and useful Improvement in Plows, of which the following is a specification.

This invention relates to the portions of a plow known as the "rolling colter and jointer." Its object is to obtain a unison of action 10 in these parts, and to obtain the necessary adjustments of the parts to render them efficient in their combined capacity and in connection with the plow. To this end I have designed 15 and constructed the apparatus represented in the accompanying drawings, in which—

Figure 1 is a plan view of an apparatus embodying my invention. Fig. 2 is a side elevation. Fig. 3 is a vertical transverse section 20 on dotted line 1. Fig. 4 is a horizontal section on dotted line 2. Fig. 5 is an isometrical representation of the mud-band, and Fig. 6 is an isometrical representation of the foot-support of the jointer.

In the figures, A represents a bracket-support to connect with the plow-beam; B, a rectangular socket to receive the bent end of the bracket, and is held in place thereon by a set-screw; C, a vertical socket to receive the 30 journal-arm of the colter-yoke, and is fitted in clutch form at its upper end. These several parts are substantially the same as like parts found in Patent No. 287,733, issued to me for improvement in rolling colters, dated October 30, 1883.

At D is represented a yoke arm, provided at its forward end with a vertical journal-arm, a, fitted to the vertical socket, and held in place therein by a pin passed through its 40 projecting end, and, in connection with the clutch portion of the socket, limits the oscillatory movements of the yoke and the parts thereto attached. The yoke-arm D, from its connection with the journal-arm, extends rearward in a downward-curving manner, as represented in the dotted lines in Fig. 2, to receive and support the journal-bearing of the colter E. The colter E is of the usual construction, and a hub, F, of conic form, is centrally fixed to one side thereof, and is pro-

vided with an axial opening of conic form to receive an axle and to revolve thereon.

At G is represented an axle-bolt produced in conic form to enter the axial opening in the hub, and is provided with a head, b, to engage the side of the colter. The end portion, c, of the axle-bolt is produced in square form to enter a square hole formed in the end of the yoke-arm.

At H is represented a mud-band having a 60 disk-head, d, provided with a square axial opening to receive the square portion c of the axle-bolt, and is placed in position on the inside of the yoke-arm to receive the outer end of the hub. The extreme outer end of the 65 axle-bolt is screw-threaded, and is provided with a screw-nut to fix the parts in place.

At I is represented a cap placed over the head of the axle-bolt.

In the preparation of the colter the axle-bolt 70 is placed in the eye or center opening of the colter. The hub is then placed on the axle-bolt, and the cap over the head thereof, and the parts are fixed in position by means of rivets or bolts passed through the flange of 75 the hub, through the blade of the colter, and through the ears of the cap. The square portion of the axle-bolt is then passed through the opening in the outer end of the yoke-arm, and by means of a screw-nut the colter is fixed 80 in position on the arms to revolve on its axle-support in connection therewith. The employment of the cap to cover the head of the axle-bolt is a complete protection against dirt or grit working into the joint, and, in connection with the mud band, operates to protect the whole bearing.

At K is represented an arm projecting laterally from the forward journal end of the yoke.

At L is represented a rectangular socket 90 fitted to receive the lateral arm of the yoke, on which it is made adjustable lengthwise, and when adjusted is fixed in place thereon by means of a set-screw, e, screw-threaded into 95 its forward end. The rear arm of the socket is provided at h, on its inner face, with a rosette saw-toothed ratchet to engage a like rosette saw-toothed ratchet, i, formed on the outer face of the forward end of a plow-beam, N, 100

in a manner to permit of a vertical adjustment of its rear end, and when adjusted is fixed in position by means of a clamping-screw passed through the axial center of the rosette-ratchets.

5 The plow-beam *N*, from its connection with the socket portion thereof, extends rearward, leaving its rear portion curved downward in a suitable manner, as shown in Fig. 2.

At *P* is represented the foot-support of the 10 jointer plowshare, having its shank portion *k* produced in concave form to engage the front convex surface of the downturned portion of the plow-beam in such a manner as to permit of a limited rolling movement thereon, and 15 capable of a vertical adjustment on the beam.

At *l* is represented a screw-clamp of loop form, to receive the plow-beam and the shank of the foot-support placed on its front edge, and its rear portion, *m*, is screw-threaded and 20 extends through a suitable washer, *n*, and receives a screw-nut, by means of which the foot-support is firmly clamped to the beam and made adjustable thereon.

At *R* is represented a share produced from 25 suitable material in the usual plow form, and is securely fixed to the foot portion *p* of the foot-support by means of holding-bolts passed through the parts, or otherwise. These several parts, consisting of the beam, share, foot-

30 support, and holding mechanism, constitute the jointer, and by reason of the adjustable connection of the plow-beam with the colter-yoke the jointer is made adjustable toward or from the colter. The rosette-ratchet connection of the two-part plow-beam provides the 35 means for the vertical adjustment of the rear end of the beam to vary the angle of the share relatively with the ground, and the adjustable connection of the foot-support of the share

40 with the beam provides the means for the vertical adjustment of the share on the beam to vary its running depth relatively with the colter, and also to vary its angle relatively with the line of travel of the colter.

45 By this connection of the jointer with the colter I produce a combination in which the oscillatory or lateral swinging movements of

the colter and jointer and their relative running depth shall be in unison, and their adjustments relatively with each other are such 50 as to meet the requirements of their joint action.

I claim as my invention—

1. In a combined rolling colter and jointer-plow, the jointer made adjustable relatively 55 with the colter laterally, substantially as and for the purpose set forth.

2. In a combined rolling colter and jointer-plow, the jointer-plow beam having a pivot-connection with the yoke of the colter, whereby 60 the angle or inclination of the jointer-plow may be varied, and means, substantially as shown, for securing said plow in adjusted position, as set forth.

3. In a combined rolling colter and jointer-plow, the jointer made adjustable laterally with relation to the colter, and also made vertically adjustable by means, substantially as shown, to vary the angle or inclination of the 65 said jointer-plow, as set forth.

4. In a combined rolling colter and jointer-plow, the jointer-plow made adjustable in its connection with its beam-support to vary its angle relatively with the line of travel of the colter, substantially as and for the purpose 75 set forth.

5. The combination, with a rolling colter capable of a lateral oscillatory movement, of a jointer-plow, said jointer-plow supported to conform to the oscillating and vertical movements of the colter, substantially as and for the purpose set forth.

6. In a combined rolling colter and jointer-plow, a two-part beam, said two-part beam having a rosette-ratchet connection, substantially as and for the purpose set forth.

7. The combination, with the colter-yoke, of a plow-beam having a socket and set-screw connection with an arm on the colter-yoke, substantially as set forth.

HENRY M. SKINNER.
